UNITED STATES PATENT OFFICE.

HENRY S. McGARRY, OF HOUSTON, TEXAS.

SLIP.

Application filed February 28, 1924. Serial No. 695,833.

To all whom it may concern:

Be it known that I, HENRY S. McGARRY, a citizen of the United States, residing at Houston, in the county of Harris and State 5 of Texas, have invented certain new and useful Improvements in a Slip, of which the following is a specification.

This invention relates to new and useful improvements in a slip.

One object of the invention is to provide 10 a slip of the character described specially designed to be inserted in a rotary table, around the pipe and provided for the purpose of holding the pipe suspended in the 15 rotary while making up, or breaking up, the string of pipe.

Another object is to provide a rotary slip, 20 formed of independent sections, each section being composed of a plurality of jaws anchored together in such manner as to permit the jaws of each section to move radially, as well as vertically, relative to each other so that the slip will engage with round pipe or with pipe of irregular cross 25 sectional contour, all the way around, and thus securely grip and hold the same suspended from the rotary.

Another object of the invention is to provide 30 a slip, of the character described which is of very simple construction, and which may, therefore, be very cheaply produced, and which is very effective in use.

With the above and other objects in view, 35 this invention has particular relation to certain novel features of construction, operation and arrangement of parts, an example of which is given in this specification and illustrated in the accompanying drawings, wherein:—

Figure 1 shows a plan view of one section 40 of the slip.

Figure 2 shows an inside elevation thereof;

Figure 3 shows a side view thereof taken 45 at right angles to the view shown in Figure 2, and, Figure 4 is a cross sectional view taken on the line 4—4 of Figure 2.

In the drawings the numerals 1 and 2, 50 respectively, designate the upper and lower arcuate end plates of the slip sections. These end plates have their facing sides provided with dovetailed grooves 3 and 4, respectively. The numeral 5 designates the jaws. The inner sides of the jaws are toothed, to engage with the pipe, and their outer sides are downwardly tapered, as

shown. The upper and lower ends of the jaws 5 are provided with the dovetailed tenons 6 and 7, which are fitted loosely into the corresponding grooves 3 and 4. As 60 shown, each section of the slip has four jaws, and the end jaws are keyed to the respective upper and lower plates 1 and 2 by means of the transverse keys 8 and 9, which fit loosely through keyways, provided for them, in the tenons 6 and 7.

The top plate 1, of each section, is provided with the outwardly beveled, spaced lugs 10, 10, between which the rod 11 is pivoted. This is accomplished by means of 70 a pin 13 whose ends are journaled in the respective lugs, and on which the rod 11 has a bearing. The outer end of this rod is formed into a grip 12, thus forming a handle, by means of which the slip section may 75 be handled. When the slip is in position for use, the handle lies back in horizontal position, and the lugs 10 protect it from being broken by the falling of heavy objects, such as are in common use on a derrick floor in 80 carrying on drilling operations.

What I claim is:

1. A slip formed of independent sections, 85 each section being composed of an upper and a lower arcuate end plate, a plurality of jaws between said plates, dovetailed end tenons on said jaws, said plates being provided with dovetailed grooves into which the corresponding tenons fit.

2. A slip formed of a plurality of sections, each section being composed of a plurality of jaws and arcuate upper and lower end plates, the respective plates abutting against the corresponding ends of the jaws and being loosely connected to said jaws by 95 means of dovetailed tenons formed on one of said abutting parts which work in dovetailed grooves in the other abutting parts.

3. A slip formed of a plurality of sections, each section being composed of a plurality of jaws, and arcuate upper and lower end plates with which the corresponding jaws articulate, said articulating parts being formed, one with a dovetailed tenon and the other with a dovetailed mortise in which 100 the tenon fits loosely.

4. A slip formed of a plurality of sections, each section being composed of a plurality of jaws, and arcuate upper and lower end plates with which the corresponding jaws 110 articulate, said articulating parts being formed, one with a dovetailed tenon and the

other with a dovetailed mortise in which the tenon fits loosely, and a handle carried by each section.

5. A slip formed of a plurality of sections, each section being composed of a plurality of jaws and arcuate upper and lower end plates, dovetailed end tenons on said jaws, said plates being provided with dovetailed grooves into which the corresponding 10 tenons fit, and means securing the jaws against detachment from said end plates.

6. A slip formed of a plurality of sections, each section being composed of a plurality of jaws, an arcuate upper end plate 15 abutting against the corresponding ends of

the jaws of each section and being loosely connected to said jaws by means of dovetailed tenons formed on one of said abutting parts which work in dovetailed grooves in the other abutting part and means for holding the lower ends of the jaws of each section in substantially arcuate alignment. 20

In testimony whereof I have signed my name to this specification in the presence of two subscribing witnesses.

HENRY S. McGARRY.
